UNITED STATES PATENT OFFICE.

OZRO H. BURNHAM, OF OAKLAND, AND JOHN J. MEYERS, OF SAN FRANCISCO, CALIFORNIA.

COLD-STORAGE STRUCTURE.

SPECIFICATION forming part of Letters Patent No. 515,285, dated February 20, 1894.

Application filed October 5, 1893. Serial No. 487,241. (No model.)

To all whom it may concern:

Be it known that we, OZRO H. BURNHAM, residing at Oakland, and JOHN J. MEYERS, residing at San Francisco, State of California, 5 citizens of the United States, have invented new and useful Improvements in Cold-Storage Structures, &c., of which the following is a specification.

The objects of this invention are to provide 10 an improved and economical system of alternate or combined refrigeration and ventilation in cold storage structures; to promote a free and easily controlled circulation of pure and dry cold air currents in the storage or 15 preserving chamber; to prevent accumulations of moisture in and adjacent to the ice receptacle, thereby economizing the consumption of ice; and to improve generally the construction of refrigerators, cooling apparatus 20 and cold storage chambers or warerooms for preservation of perishable goods.

The invention consists in the features of construction and novel combination and arrangement of parts in a cold storage structure 25 as hereinafter described and claimed.

In the annexed drawings, illustrating the invention—Figure 1 is a vertical section, from front to rear, of a refrigerator or cold storage ware room or structure embodying our improvements. Fig. 2 is a perspective of a cold 30 storage structure or refrigerator having a modified form of outer casing suitable for market stores, dairies, restaurants, &c., and showing the upper portion of the front of the casing partly broken away to expose the interior with one of the valves for controlling the circulation of air for refrigeration or ventilation of the storage chamber.

The top, bottom, side and end walls of our 35 refrigerator or cold storage structure may each be made complete in itself with permanent corner sections 1 capable of having a detachable air tight connection, by tongue and groove or rabbet joint, with the similar 40 corner section of an adjacent part or side to form a knockdown structure of the character described in Letters Patent No. 471,944 granted to us March 29, 1892. Each wall of the structure, and also the top and bottom or 45 floor, comprises, besides the corner sections 1, several thicknesses of the best kiln dried

board 2, paraffine paper 3 and mineral wool packing 4 with intervening air spaces 5, if desired. The corner sections 1 and boards 2 in each part are permanently connected in 55 such manner as to inclose the intermediate air spaces, mineral wool and paraffine paper and make of each composite part, (top, bottom or side as the case may be) a complete insulated section capable of being detachably connected at the joints 6, Fig. 1, with the other similar wall sections so that the entire structure will be effectively insulated and made air tight and capable of being readily taken apart and packed in a small space for 60 transportation or when not required for immediate use.

In the upper part of the cold storage structure or refrigerator casing 7 are bearings 8 for the transverse beams or girders 9 on which 70 are supported the longitudinally arranged slats 10 that form the bottom of the ice rack. The sides of the ice rack 11 are composed of longitudinally arranged slats 12 secured in vertical series to the inner sides of double 75 vertical partitions 13 preferably composed of kiln dried boards and inclosing air spaces 14 by which the sides of the ice rack are insulated. The double partitions 13 are supported on the girders 9 and are extended 80 downward between and beneath the same to connect with the sides of a drip tray 15 arranged below the girders and ice rack. To the outer sides of the vertical double partitions 13 are secured upright braces 16 that 85 serve to strengthen the said partitions and are also extended down between the girders 9 to assist in supporting the drip tray.

The drip tray or pan 15 is constructed in two opposite downwardly and inwardly inclined 90 sides the outer edges of which have a perfectly air tight connection with the lower ends of the partitions 13 so as to make it impossible for any cold air to pass over the edges of said pan or tray and thereby interfere with or 95 check the required circulation which is essential to the maintenance of dry air currents in the proper direction through the refrigerating or cold storage apparatus. This drip pan or tray 15 is preferably made of double thickness, with perforations at the sides and in the outer or lower thickness to permit a free cir-

culation of dry air between the inner and outer linings or thicknesses and thus prevent condensation on the bottom of the pan. In the center of the drip tray or pan, between its two opposite downwardly and inwardly inclined sides, is a longitudinal opening or space constituting a cold air flue or passage 17 for the cold air to pass down into the storage or preserving chamber 18 from the ice rack or refrigerating compartment occupying the upper part of the structure.

Above the cold air flue 17 is a drainage hood 19 supported on brackets 20 resting on the inside of the drip tray bottom. The hood 19 is constructed of double thickness with a hollow ventilated interior similar to the construction of the drip pan and is provided with a zinc or galvanized iron covering 21 extended out beyond the body of the hood a sufficient distance to prevent water from backing up under the hood and dripping into the storage chamber. Between the drip pan or tray 15 and the under sides of the girders 9, beneath the ice rack 11, is a space 22 several inches in depth at the outer sides and gradually increasing toward the center by the incline downward and inward of the two opposite sides of the drip tray. Through this space 22 the drip from the melting ice in the ice rack falls onto the hood 19 and drip tray 15 and is conducted thence through converging drainage pipes 23 connected with a trap 24 having an escape pipe 25 leading to the outside of the refrigerating structure.

35 The trap 24 may be provided with a valve or cock 26 and is so arranged as to allow the drip or drainage water to escape freely and yet retain the cold air.

Between the ice rack 11 and the top and front and rear walls of the refrigerator casing is a curved partition 27 having its central top portion extended upward in the form of a double incline 28 which is arranged to project partly into an inverted funnel shaped ventilator opening 29 in the top of the refrigerator. The curved partition 27 divides the space between the ice rack 11 and the refrigerator walls into inner warm air flues 30, leading from the preserving or storage chamber 18 upward and over into the ice rack, and outer ventilating flues 31 leading from the preserving or storage chamber to the ventilator opening 29 in the top of the structure. To the opposite lower ends of the partition 27 are hinged shutters or flap valves 32 arranged to control the passage of air through the flues 30 and 31 for alternate refrigeration or ventilation of the preserving or storage chamber 18 or for a combined refrigeration and ventilation of said chamber, as may be required. The valves 32 may be shifted outward across the flues 31 for closing the latter and causing all the air currents from the preserving or storage chamber to pass upward through the inner flues 30 and over the partitions 13 into the ice rack or refrigerating compartment and thence downward beneath the hood 19

and through the centrally arranged cold air flue 17 into the preserving or storage chamber, thus keeping up a constant circulation 70 of pure, dry cold air. The outward shifting of the valve 32 is preferably effected by employing ordinary spring hinges to connect the valves with the partitions, such spring hinges tending to constantly press the springs 32 75 outward or across the flues 31. When the valves 32 are shifted inward in such a manner as to close the flues 30 and open the ventilating flues 31 air from the preserving or storage chamber 18 will be permitted to pass 80 out through said flues 31 to and through the ventilator opening 29 thus ventilating the structure and removing any warm moist air that it may have contained. One of the valves 32 may be left open and the other 85 closed so as to permit ventilation from one side of the storage chamber at the same time that circulation is kept up between the storage chamber and the ice receptacle.

The valves 32 may be regulated by means 90 of vertically arranged levers 33 attached to the lower outer portions of the partitions 13 in position to be operated from the inside of the storage chamber. At their upper ends these levers are connected by chains or rods 95 34 with the lower edges of the valves and the said levers and chains or rods are so arranged that by raising or lowering the levers the valves can be shifted inward or outward, as desired. The levers 33 may be provided with 100 ratchet teeth 35 for engaging any suitable catch 36 to hold them in adjusted position.

It will be observed that when the ventilating flues 31 are closed there is an entirely free circulation of dry cold air around the 105 ice or refrigerant at top, bottom, sides and ends. The ice receptacle or rack is so constructed that the ice will nowhere touch a perfectly flat or smooth unbroken surface. A free circulation of cold, dry air is thus permitted and accumulations of moisture prevented at any point. The ventilated and insulated construction of the drip tray and its 110 hood is also such as to prevent accumulations of moisture and assist a free circulation of dry cold air in the ice receptacle and from the same through the cold air flue 17 into the preserving or storage chamber. The 115 ventilating flues 31 are wholly separated from the ice receptacle 11 by the intervening partition 27 in such manner that in ventilating the storage chamber no warm moist air can gain access to the refrigerant material. A greater saving of ice and a lower temperature are thus permitted than is possible in 120 other than a dry cold atmosphere.

The form of the ventilator opening 29—shaped like an inverted funnel with its upper or smaller diameter not more than one fifth of its lower diameter—prevents displacement of the colder and heavier air in the refrigerator by the warmer and lighter external atmosphere. It is preferable to curve the upper corners or angles of the flues 30

and 31 by giving a curvature at these points to the partition 27, as shown, thereby avoiding any tendency to obstruction of currents as is likely with corners constructed at right angles. By constructing the top of the partition 27 with the double incline 28 extended upward into the ventilator opening 29 a guide is provided to prevent contact of opposing air currents that would have a tendency to check 10 ventilation.

The improvements herein described are equally applicable in the construction of permanent cold storage warehouses or cooling rooms or to refrigerators of a portable type. 15 For use in market stores and similar places the refrigerator casing 7 may be constructed with an offsetting lower portion 37, as shown in Fig. 2, in order to give increased capacity to the preserving or storage chamber without increasing the width of the overhead ice receptacle.

What we claim as our invention is—

1. The combination with a cold storage structure having a storage chamber, a refrigerant chamber, a ventilator opening in its upper part, and flues leading, respectively, from the storage chamber to the refrigerant chamber and ventilator opening, of a movable valve located and supported within the cold storage structure and movable into one position for closing the flue leading to the ventilator opening and into another position for opening said flue leading to the ventilator opening and closing the flue leading to the refrigerant chamber, substantially as described. 30

2. The combination in a cold storage structure having a ventilator-opening in its upper part and a preserving or storage chamber in its lower part, of a receptacle for refrigerating material intermediate the storage chamber and ventilator opening, a partition located above and at the sides of the receptacle for refrigerating material, warm air flues leading on the inner side of said partition from the storage chamber to the upper part of the receptacle for refrigerating material, ventilating flues on the outer side of said partition for conducting warm moist air from the storage chamber to the ventilator-opening, valves located at the lower ends of the ventilating flues, and a cold air flue leading centrally from the receptacle for refrigerating material downward to the storage chamber, substantially as described. 45

3. The combination in a cold storage chamber having an inverted funnel shaped ventilator-opening in its top, and a preserving or storage chamber in its lower part, of a recep-

tacle for refrigerating material intermediate the storage chamber and ventilator opening, 60 a partition located above and at the sides of said receptacle and provided on its upper side with a double inclined guide projection extended partly into the ventilator-opening, warm air flues leading on the inner side of 65 said partition from the storage chamber to the upper part of the receptacle for refrigerating material, ventilating flues on the outer side of said partition for conducting warm moist air from the storage chamber to the 70 ventilator-opening, valves located at the lower ends of the ventilating flues to alternately control the warm air flues and ventilating flues, and a cold air flue leading centrally from beneath the receptacle for refrigerating 75 material to the storage chamber, substantially as described.

4. The combination in a cold storage structure having a ventilator-opening in its top and a storage chamber in its lower part, of an ice 80 rack intermediate the storage chamber and ventilator opening, a drip pan or tray located below the ice rack and provided with a central cold air flue, a hood located above said flue, warm air flues leading from the storage 85 chamber to the upper part of the ice rack, ventilating flues for conducting warm moist air from the storage chamber to the ventilator-opening, and valves located at the lower ends of the ventilating flues and adapted to 90 control said warm air flues and ventilating flues for alternate or combined ventilation and refrigeration of the storage chamber, substantially as described.

5. The combination in a cold storage structure, of a storage chamber located in the lower portion of said structure, a receptacle for refrigerating material located in the upper part of the structure below a ventilator-opening in the top of the structure, a partition between 100 said receptacle and the top and sides of the outer casing, ventilating flues on the outer side of said partition to conduct warm moist air from the storage chamber to the ventilator-opening, and valves movable across the 105 lower ends of said ventilating flues to control the ventilation and refrigeration of the storage chamber, substantially as described.

In testimony whereof we have hereunto set our hands in presence of two subscribing witnesses.
